UNITED STATES PATENT OFFICE.

MILTON W. SHEAFFER, OF HANOVER, PENNSYLVANIA.

HEADLIGHT.

Application filed May 13, 1925. Serial No. 30,100.

This invention relates to headlights and more particularly to a headlight construction for automobiles which is adapted to project a brilliant substantially central road lighting beam surrounded by rays of lesser intensity to provide illumination at the edges of the road, on the road close to the vehicle and to provide sufficient illumination to permit the driver of the vehicle to detect any overhead obstructions.

An important object of the invention is to provide a peculiar form of reflector, the rear portion of which is adapted to project slightly converging rays which will be intercepted by the lens and refracted thereby to provide a brilliant road light which is projected in such a manner as to prevent glaring in the eyes of approaching drivers.

A further object is to provide a headlight of the above mentioned character wherein the lens employed is surrounded by semi-transparent or translucent glass through which light passes from the forward portion of the reflector to provide sufficient scattered light to illuminate ditches, etc.

A still further object is to provide novel supporting means for the lens and translucent glass, such means being provided with a portion adapted to shape the intense central beam passing from the headlight.

Other objects and advantages of the invention will become apparent during the course of the following description.

In the drawings I have shown several embodiments of the invention. In this showing:

Figure 1 is a central longitudinal sectional view through the headlight,

Figure 2 is a front elevation,

Figure 3 is a view similar to Figure 1 showing a slightly modified form,

Figure 4 is a perspective view of the form of lens holder employed in connection with the form of the device shown in Figure 1, and

Figure 5 is a similar view showing the modified form of lens holder.

Referring to the drawings, the numeral 10 designates a casing provided at its forward end with an internal annular flange 11. The casing is provided with an axial opening to receive a tubular member 12 which forms a socket for the lighting unit employed. As shown, the tubular member is provided in its rear end with a bayonet slot 13 to receive a pin 14 carried

by a connecting plug 15. The tubular member is provided at its inner or forward end with a second bayonet slot 16 to receive a pin 17 carried by the base of an incandescent bulb 18. It will be apparent that the bulb is adapted to receive current through the plug in the usual manner.

A reflector designated as a whole by the numeral 19 is arranged within the casing as shown in Figure 1 and this reflector is provided with an axial opening in its rear end through which the socket 12 projects. In practice I prefer to employ a reflector 19, the rear portion 20 of which is preferably an ellipsoid while the forward portion 21 approximates a parabola. It will be apparent that the rays reflected from the rear portion of the reflector 19 will converge while those reflected from the forward portion 21 will pass outwardly through the front of the reflector substantially parallel to the axis thereof.

As shown in Figures 1, 2 and 3, a supporting member 22 is arranged at the forward end of the casing and reflector. As shown, the supporting member is provided with an outer annular ring 23 which is provided with a substantially cylindrical flange 24 which may be slipped over the outer end of the casing 10, as shown. The supporting member is further provided with a substantially tubular central portion 25 which is connected to the ring 23 by arms 26, as clearly shown in Figure 4. The arms 26 are preferably thin so as not to intercept any great percentage of the light passing from the forward end of the casing. A translucent or semi-transparent glass 27 is arranged between the ring 23 and flange 11, as shown in Figure 1. The glass 27 is provided with a central opening 28 so that rays of light from the bulb and rear portion of the reflector will pass directly through the tubular member 25 as will be obvious. A packing ring 29 is preferably arranged between the glass 27 and flange 11 and screws 30 pass through the ring 23 and flange 11 to secure the elements together.

The tubular member 25 has certain portions of its inner walls inclined inwardly toward its center, as shown at 31 to provide an opening in the rear end of the tubular member as shown by the dotted lines in Figure 2. A lens 32 is arranged in the forward end of the tubular member 25 and is retained in position by a resilient ring 33.

2
In practice I prefer to employ a reflector having its rear portion formed as an ellipsoid of such proportions that the conjugate focus thereof will lie between the lens 32 and the rear end of the tubular member 25.

In the form of the invention shown in Figures 3 and 5, I prefer to use a reflector, casing and lighting means similar to those previously described. In the modified form 10 of the device, however, I employ a support 34 which differs somewhat from the support 22. In this form the support is provided with an outer substantially flat ring 35 which is adapted to be arranged directly against the flange 11 of the casing. A lens supporting member or tube 36 is arranged centrally of the support as shown in Figures 3 and 5 and a lens 37 is arranged in the rear end of the tube. A resilient ring 38 is 15 adapted to retain the ends 37 in position. The tube 36 has certain of its walls 39 inclined inwardly to provide a forward contour as indicated in Figure 5. It will be noted that the forward end of the tube 36 20 has a flat upper wall 40 and inclined side walls 41. The ring 35 and tube 36 are connected by arms 42 similar to the arms 26 except that they turn inwardly into the interior of the reflector. The tube 36 projects forwardly a slight distance beyond the 25 arms 42 and a semi-transparent or translucent glass 43 is provided with a central opening to receive the forward end of the tube 36. A packing ring 44 is arranged between the glass 43 and ring 35 and a cap 46 is 30 arranged against the outer face of the glass as shown. The cap 46 is provided with a cylindrical flange 47 to receive the forward end of the casing 10 and the cap 46 is secured to the flange 11 by screws 48. The portion of the reflector employed in connection with the modified form of the device 35 also is so proportioned that its conjugate focus will lie intermediate the ends of the tube 36. Thus it will be apparent that the beam from the ellipsoidal portion of the reflector will be intercepted by the lens 37 rearwardly of the conjugate focus.

The operation of the form of the device 40 illustrated in Figures 1, 2 and 4 is as follows:

Light reflected from the ellipsoidal portion of the reflector will converge toward the conjugate focus of the reflector and the outer 45 portion of the beam thus projected will be intercepted by the rear end of the lens supporting tube 25. Thus the beam will be shaped according to the configuration of the inside of the member 25 and after the 50 rays pass the conjugate focus of the ellipsoid they will be refracted and redirected by the lens 32 to confine them within the proper legal limits. The shape of the beam thus projected may be governed in any desired manner by changing the shape of the 55

inner end of the lens support 25 as will be obvious. The light from the forward portion 21 of the reflector and stray light from the rear portion 20 of the reflector, will pass through the glass 27 and will be scattered somewhat thereby to light the edges of the road, the road close to the vehicle and also the upper atmosphere to permit the driver of a vehicle to detect any overhanging obstacles. The light through the 75 glass 27, however, will be softened materially so as to cause no glare in the eyes of operating drivers. If desired, the outer surface of the supporting member 25 may be polished to a reflecting surface to reflect any 80 light intercepted thereby. The lens 32 may be either double convex as shown, or plano-convex as will be obvious. The inclined walls 31 in this form of the device are arranged at the bottom of the lens supporting member inasmuch as the rays passing these walls will form the upper portion 85 of the resultant beam, as will be obvious.

In the form of the invention shown in Figures 3 and 5 the inclined walls of the 90 lens supporting member are arranged at the upper portion thereof inasmuch as the forward end is arranged outwardly beyond the conjugate focus of the ellipsoid. Inasmuch as the lens in this form of the device 95 is arranged rearwardly of the conjugate focus, it will be apparent that it is desired to employ either a double concave or a plano-concave lens.

It is to be understood that the forms of 100 my invention herewith shown and described are to be taken as preferred examples of the same and that various changes in the shape, size and arrangement of parts may be made without departing from the spirit 105 of the invention or the scope of the subjoined claims.

I claim:

1. A headlight comprising a reflector formed as a surface of revolution and provided with an open end, a light source arranged in said reflector, a glass arranged in the open end of said reflector and provided with a central opening, a lens arranged in the path of travel of rays of light passing through the opening in said glass, the rear portion only of said reflector being adapted to project converging rays toward said lens, and means associated with said lens and adapted to intercept a portion of the light from the rear portion of said reflector for determining the shape of the upper limit of the beam projected by the light converging portion of said reflector.

2. A headlight comprising a reflector formed as a surface of revolution and provided with an open end, a light source arranged in said reflector, a glass arranged in and substantially filling the open end of said reflector, said glass being provided with

a central opening, a lens holder arranged adjacent the opening in said glass and provided with a central elongated opening, and a lens arranged in one end of the opening in said holder, the opposite end of said last named opening being shaped to intercept a portion of the light from said reflector, determine the shape of and to provide a sharp cut-off at the upper limit of the beam passing through said lens.

3. A headlight comprising a reflector formed as a surface of revolution and provided with an open end, the rear portion of said reflector being substantially ellipsoidal, a light source arranged at the focus of the ellipsoidal portion of said reflector, the forward portion of said reflector being adapted to intercept rays of light from said source and reflect them toward the open end of said reflector in substantially parallel lines, a glass arranged in and substantially filling the open end of said reflector and provided with a central opening, a support arranged adjacent said glass, a relatively long substantially tubular lens holder carried by said support, and a lens arranged in one end of said holder in alignment with the opening in said glass and in the path of rays from the ellipsoidal portion of said reflector, the opposite end of said holder being adapted to intercept some of the outer rays of the beam from said ellipsoidal reflector portion to determine the shape of the beam passing through said lens.

4. A headlight comprising a casing, a reflector arranged in said casing and formed as a surface of revolution, said reflector being provided with an open forward end, the

rear and forward portions of said reflector being substantially ellipsoidal and parabolic respectively and merging one into the other, a light source arranged in said reflector, a glass arranged against the open end of said reflector and provided with a central opening, a support arranged outwardly of and against said glass and secured to said casing, said support including a central tubular portion, an outer ring portion, and arms connected between said ring and tubular portions, and a lens arranged in the tubular portion of said support in the path of rays from the ellipsoidal portion of said reflector.

5. A headlight comprising a reflector formed as a surface of revolution and provided with an open end, a light source arranged in said reflector, a glass arranged in the open end of said reflector and provided with a central opening, a member arranged at the periphery of said glass, an inwardly extending radial arm carried by said member, a lens holder carried by said arm at its inner end, a lens carried by said holder and arranged in the path of travel of light rays passing through the opening in said glass, the rear portion of said reflector being adapted to project converging rays toward said lens and a beam shaping member associated with said lens holder and having a portion spaced from said lens and projecting into a portion of the light passing from the rear portion of said reflector to said lens to determine the shape of the beam passing therethrough.

In testimony whereof I affix my signature.

MILTON W. SHEAFFER.
